UNITED STATES PATENT OFFICE

NICHOLAS P. MANDRICH, OF BROOKLYN, NEW YORK

ADJUSTABLE MONOPLANE

Application filed February 14, 1930. Serial No. 428,409.

This invention relates to aeroplanes and is particularly adaptable to monoplanes.

An object of the invention is to provide a monoplane that is designed with special adjustments to improve the safety of the aero-plane.

Another feature of the invention is to provide for regulation of the wings at increased or decreased speeds and to further provide a short fuselage and extensible wings, which would be more readily controlled.

A further feature of the invention is to provide a triangular nose wing, rockable on a horizontal axis, the apex of which is in alignment with the nose of the fuselage to prevent diving at the take-off or landing, and at the same time to provide for safe control in the event of motor trouble.

Further objects of the invention are to provide in a manner as hereinafter set forth, an aeroplane of the character referred to, that is strong, compact and durable, thoroughly reliable for its intended purpose, very easy in its method of assembly, and comparatively inexpensive to manufacture and operate.

With the foregoing and other objects in view, the invention consists in the novel arrangement, combination of parts as will be hereinafter more specifically described and illustrated in the accompanying drawings, but it is to be understood that changes, variations and modifications may be resorted to, without departing from the spirit of the claims hereunto appended.

In the drawings, wherein like reference characters denote corresponding parts throughout the several views:

Figure 1 is a side elevation of the aeroplane in accordance with the present invention.

Figure 2 is a top plan view thereof.

Figure 3 is a fragmentary horizontal section, taken substantially on lines 3-3 of Figure 1 and looking in the direction of the arrows.

Figure 4 is a fragmentary vertical section through the stationary transverse wing, taken substantially on the line 4-4 of Figure 2 and looking in the direction of the arrows.

Figure 5 is a transverse section in detail, and taken substantially on line 5-5 of Fig-

ure 2 and looking in the direction of the arrows.

Figure 6 is a longitudinal vertical section in detail, and taken substantially on line 6-6 of Figure 2 and looking in the direction 55 of the arrows.

Figure 7 is a vertical longitudinal section in detail, through the fuselage and wing taken substantially on the line 7-7 of Figure 2 and looking in the direction of the arrow, and 60

Figure 8 is a transverse vertical section in detail, taken through the longitudinal wing and fuselage, substantially on the line 8-8 of Figure 2 and looking in the direction of the arrows. 65

Referring to the drawings in detail, 9 indicates generally a cigar shaped fuselage, disposed longitudinally with the blunt end forward and the pointed end to the rearward. 70 On the blunt end 10 of the fuselage is supported the motor 11, projecting forwardly from which and rotatably connected therewith is the main propeller 12, the intermediate portion of the fuselage 9 being used for carrying passengers or freight and is provided with windows 13 and a door 14. 75

Forwardly of the central compartment is the cockpit 15, having a forward wall 16 and an instrument board 17 at the upper end of the forward wall. At the upper portion of the cockpit, there is provided window panels 18 that extend around three sides of the cockpit to provide vision from all angles. 80

At the rear of the fuselage is a vertical up-standing fin 19, to the trailing edge of which is rockably connected the rudder 20 and on each side of the rudder are the elevating planes 21 that are rockably connected at their leading edges to oppositely disposed lateral fins 22. 85

The rudder and elevator planes are connected with the conventional control wires (not shown) which extend into the cockpit 15, within reach of the pilot.

Intermediate the ends of the fuselage 9, 95 there is a flat, transverse stationary horizontal wing 23 disposed in tangential relation to the top of the fuselage, and secured thereto by any suitable means. The stationary horizontal wing 23 projects from each side of the fuse- 100

lage at equal distances. From the trailing edge of the portions of the stationary wing 23 extend the conventional ailerons, 24, 25, and these ailerons are rockably connected to the trailing edges of the extending portions. The ailerons may be controlled by any conventional means within the reach of the pilot in the cock pit 15. The upper face 26 and lower face 27 are suitably spaced from each other by channel bars 28, 29, which are co-extensive with the leading and trailing edges thereof. The space between the upper and lower faces of the wings provides a transverse pocket 30 throughout the entire length of the wings.

The ends of the stationary transverse wing 23 are open to receive the extensible sections 31, 32, which slide in and out of the pockets 30. Along the webs of the channel bars 28, 29, there are mounted a plurality of spaced rollers 33, 34, which bear against the leading and trailing edges of the extensible sections 31 and 32. At the opposite ends of the stationary wings, there are also a series of rollers 35, 36, which are secured to the ribs on the upper and lower faces 26, 27, respectively that bear against the upper and lower faces of the lateral wing sections so as to facilitate the movement of the wing sections with ease and dispatch. The longitudinal ribs 37 of extensible wing sections 31, and the longitudinal ribs 38 of extensible wing sections 32, extend beyond the confronting ends of these wing sections into the pockets 30 of the stationary wings. These oppositely extending rib extensions 37 and 38 are disposed between each other, so as not to interfere with their movement. A cone clutch 39 is mounted on the lower portion of a threaded rod 40 and is threadably supported on a bracket 41, which bracket is secured to the channel bar 28. Connected to the cone clutch 39 is a hand wheel 42, that extends into the attachment for moving the cone clutch 39 up or down. A transverse rod 43 is slidably mounted on the channel bars 28 and 39 and is formed at the forward end with plates 44, in which there is a slot 45. The cone clutch 39 extends through the opening or slot 45, so that when the cone is moved upwardly the rod 43 will be moved to the left and vice versa. A plurality of brake levers 46 are pivotally mounted adjacent their upper ends as at 47, and these brake levers 46 have cam surfaces 48 on their upper ends that engage with the rib extensions 37 and 38. There is one brake lever for each rib extension. The lower ends of the plurality of brake levers are connected with the transverse rod 43, so that when the cone clutch moves the rod, the cam faces 48 will bear against or retract from the rib extensions.

It therefore follows that the wing extensions 31 and 32 may be locked by the brake levers in any desired position. A pair of rack

bars 39, 50, slide in openings in a pair of cross bars 51, and 52, and these rack bars 49, 50, have teeth along their inner longitudinal edges which engage with a pinion 53, that is secured to a vertical shaft 54, that is journaled through a pocket 30 in the wings. The lower end of the shaft 54 has mounted thereon a hand wheel 55, which is in the cockpit of the aeroplane within reach of the pilot. The inner ends of the rack bars are each provided with abutment lugs 56, 57, which abut against the cross bars 51, 52, to limit the outward movement of the respective extensible extensions 31, 32. The outer ends of rack bars 49, 50, are respectively connected to the confronting ends of extensible sections 32, 31. In view of the foregoing, it will be seen that movement of the hand wheel 55, causes rack bars 49 and 50 to move inwardly causing the extensible sections to move inwardly into the pockets or outwardly therefrom as desired.

To the leading edge of the stationary transverse wing 23 is rockably connected the triangular shaped wing indicated generally at 59. The trailing edge of this triangular wing is mounted on a shaft 60 that is supported co-extensive with the leading edge of the stationary transverse wing 23, on brackets 61, the inner ends of which are secured to the channel bars 28.

The wing 59 is in the shape of an isosceles triangle, the face of which forms the trailing edge, and the apex thereof the leading edge. The apex of the wing is located adjacent the nose of the fuselage. The upper face 62 of the triangular wing is flat and the lower edge 63 of the triangular wing is flat. These flat faces decline forwardly from the trailing to the leading edge, forming a relatively sharp point at the apex of the wing.

An operating rod 64 is pivoted to the lower face 63 of triangular wing 59, and extends through a sleeve 65, on the top wall of the fuselage. The inner end of the rod 64 is threaded as at 62 and the threaded portion extends through openings in a gear housing 67 that is suitably supported. Vertically mounted in the gear housing 67 on the threaded end of the rod 64 is a sleeve 68, on which there is a miter gear 69. This miter gear 69 engages with a miter pinion 70, on the end of the rod 71 and is journaled through an opening in the forward wall 16 of the cock pit 15. On the inner end of this rod 71 is a hand wheel 72 that is operated by the pilot. Depending from the lower face 63 of the wing 59 is a bar 73, which extends through an opening in the fuselage, and the inner end of this bar 73 is calibrated as at 74, to give the angle of inclination of the triangular wing 59. The calibrations on the rod 73 are behind a glass panel 75 mounted in the instrument board 17 so that the calibrations may be seen by the pilot.

It therefore follows that by the operation of hand wheel 72, the internally threaded sleeve 68 moved by the miter gear 69 will cause the rod 64 to move up or down to change the inclination of the triangular wing 59.

A longitudinal wing is indicated generally at 76. The leading edge of the longitudinal wing 76 merges with an intermediate portion of the trailing edge of the stationary transverse wing 23. The longitudinal wing 76 is materially longer than the width of the transverse wing and also materially longer than the altitude of the triangular wing 59. The longitudinal median of the wing 76 is along the center line of the fuselage and coincides with the center of the transverse wing and the altitude of the triangular wing. This wing 76 is disposed tangentially with respect to the upper wall of the fuselage and is suitably supported thereby. The longitudinal wing 76 is transversely curved as will be clearly understood by referring to Figure 8 of the drawing. The trailing edge of the longitudinal wing terminates forwardly of the vertical wing 19 that supports the rudder. On the top of the wing 76 is a hingedly connected door 77 by which access may be had to the interior of the fuselage.

Depending from the rear end of the fuselage 9 is a tail skid 10. Supported laterally from the sides of the fuselage are a pair of angular struts 79, 80, on the lower ends of which are supported ground engaging wheels 81.

These brackets are intermediate the ends of the fuselage and forwardly of the center thereof. To each strut 79, 80, are connected the lower ends of supporting brackets 83 and the upper ends of these brackets are connected to the lower face 27 of the stationary horizontal section 23. Mounted on the brackets 82 and 83 are internal combustion engines 85, 86, that drive the auxiliary propellers 87, 88. The propellers 87, 88, are disposed laterally of the main propeller 12 and rearwardly therefrom. Furthermore, the propellers 87, 88, are disposed under the triangular wing 59.

It is to be understood that various changes in the shape, size and arrangement of parts may be resorted to, without departing from the spirit of the invention or the scope of the appended claims.

Having described the invention, what is claimed as new is:

1. An aeroplane comprising a fuselage, a transverse extensible wing secured to the top of the fuselage, and projecting from both sides thereof, a triangular wing rockably connected along its base to the leading edge of said transverse wing, and a stationary longitudinal wing extending from an intermediate portion of the trailing edge of said transverse wing.

2. An aeroplane comprising a fuselage, a

transverse extensible wing secured to the top of the fuselage, and projecting from both sides thereof, a triangular wing rockably connected along its base to the leading edge of said transverse wing, and a stationary longitudinal wing extending from an intermediate portion of the trailing edge of said transverse wing, said longitudinal wing being transversely curved.

3. An aeroplane comprising a fuselage, a transverse extensible wing secured to the top of the fuselage, and projecting from both sides thereof, a triangular wing rockably connected along its base to the leading edge of said transverse wing, and a stationary longitudinal wing extending from an intermediate portion of the trailing edge of said transverse wing, said longitudinal wing being transversely curved, upper and lower faces of said triangular wings oppositely declined from the trailing to the leading edge.

4. An aeroplane comprising a fuselage, a transverse extensible wing secured to the top of the fuselage, and projecting from both sides thereof, a triangular wing rockably connected along its base to the leading edge of said transverse wing, and a stationary longitudinal wing extending from an intermediate portion of the trailing edge of said transverse wing, said extensible wing formed with a central stationary section having a pocket extending throughout its length, and lateral wing sections movably mounted in the pocket.

5. An aeroplane comprising a fuselage, a transverse extensible wing secured to the top of the fuselage, and projecting from both sides thereof, a triangular wing rockably connected along its base to the leading edge of said transverse wing, and a stationary longitudinal wing extending from an intermediate portion of the trailing edge of said transverse wing, said extensible wing formed with a central stationary section having a pocket extending throughout its length, and lateral wing sections movably mounted in the pocket, 100 rack bars extending inwardly from each lateral section, a pinion supported in the stationary section between the rack bars, and means for turning the pinion to move the lateral sections.

6. An aeroplane comprising a fuselage, a transverse extensible wing secured to the top of the fuselage, and projecting from both sides thereof, a triangular wing rockably connected along its base to the leading edge of said transverse wing, and a stationary longitudinal wing extending from an intermediate portion of the trailing edge of said transverse wing, said extensible wing formed with a central stationary section having a pocket extending throughout its length, and lateral wing sections movably mounted in the pocket, 120 and means supported in the stationary wing section for moving said lateral sections.

7. An aeroplane comprising a fuselage, a

transverse extensible wing secured to the top of the fuselage, and projecting from both sides thereof, a triangular wing rockably connected along its base to the leading edge of said transverse wing, and a stationary longitudinal wing extending from an intermediate portion of the trailing edge of said transverse wing, said extensible wing formed with a central stationary section having a pocket extending throughout its length, and lateral wing sections movably mounted in the pocket, and means supported in the fuselage and engaging the triangular wing for tilting the wing on its axis.

the wing on its axis, and means depending from the triangular wing into the fuselage for registering the inclination of the wing.

In testimony whereof I affix my signature.
NICHOLAS P. MANDRIGLI

NICHOLAS P. MANDRICH.
